UNITED STATES PATENT OFFICE.

WILLIE NOEL MAGEE, OF HAYNESVILLE, LOUISIANA.

VALVE CAGE.

Application filed June 23, 1927. Serial No. 201,014.

My invention relates to valve cages for use in working barrels of oil wells and has for its object to interpose a device of this character in the pump rod of the well normally preventing the downward flow of fluid therein while the pump rod is being operated, but which may be opened to prevent the return of the oil in the upper portion of the casing to the well whenever it is desired to withdraw the pump rod or casing therefrom.

It is frequently necessary during the pumping operation to pull the pipe or casing from the well in order to repair or replace the parts of the pump rod, such as the pump valve, and unless some means is provided for permitting the oil in the upper portion of the casing to return to the well the same becomes wasted as the various sections of the casing are withdrawn. Such waste may amount to 20 from twelve to fifteen barrels of oil each time the casing is withdrawn, which frequently occurs every day or two. My invention, therefore, is directed to prevent such waste by permitting the oil in the upper part of the casing to return to the well and by so doing it is apparent that the weight of the casing is greatly decreased, thereby enabling the same to be more readily withdrawn.

A further object of the invention is to provide means extending outwardly of the well for operating the valve within the cage while the same is suspended downwardly within the well.

Another object is to provide a valve cage of this character which is simple in construction, strong and durable, reliable in performance, and inexpensive to manufacture and install.

Other objects and advantages reside in the special construction, combination and arrangement of the various elements forming the invention as more fully hereinafter described and claimed, reference being had to the accompanying drawings forming part hereof, wherein:

Figure 1 is an elevational view showing my valve cage ready for attachment to a pump rod,

Figure 2 is a vertical sectional view there-

50 through showing the valve in closed position,

Figure 3 is a similar view showing the

valve in open position,

Figure 4 is a perspective view of the rotat-

ing stem,

55 Figure 5 is a transverse sectional view

taken substantially along the line 5—5 of Figure 2, and

Figure 6 is a similar view taken along the line 6—6 of Figure 3.

Referring now to the drawing I have shown 60 my invention comprising a valve cage comprising a casing 5 of tubular formation and having a plurality of vertically extending slots 6 arranged near its lower end thereof, said casing having its lower end internally 65 threaded as at 7 for attaching the same to a pump rod 8 or the like. Within the lower end of the casing 5 is arranged a valve seat 9 upon which is arranged a ball valve 10, the ball being of a sufficiently reduced diameter 70 to permit of a slight transverse movement thereof within the casing.

The upper end of the casing has an opening formed therein through which is inserted 75 a stem 11 having a threaded upper end 12 for connecting with a pump rod section or the like and an annular flange 13 arranged adjacent thereto and adapted to provide abutting means for the upper end of a coil spring 14 arranged about the stem, the lower end of 80 which is adapted to rest upon the upper end of the casing 5, the spring being arranged to maintain the stem 11 normally in outwardly extending position.

The lower end of the stem is of a reduced 85 diameter and is provided with a pair of spirally arranged ribs 16 adapted to be vertically slidable within similarly formed grooves 17 formed in the opening at the upper end of the casing 5. In this manner a tight fit is 90 provided for the stem within the opening but at the same time will permit of the rotation of the stem independent of the casing.

At the lower end of the stem within the casing is arranged a collar 18 being fixedly secured thereto by a key 19 or the like carried by the stem. The lower face of the collar 18 is formed with a series of ratchet teeth 20 engaging similar teeth formed on the upper face of a collar 21 freely mounted on the end of said stem. The collar 21 is prevented from removal from the stem by a transversely arranged pin 22. A coil spring 23 is arranged upon the stem abutting the end of the casing and the collar 18 whereby to retain the ratchet teeth 20 of the respective collars in engaged position.

A hollow shell 24 is integrally formed on the lower edge of the collar 21 extending downwardly within the casing and having a 110

plurality of vertically formed slots 25 adapted to register with the slots 6 of said casing. The sleeve 24 is adapted to form a tight fit within the casing so that when the valve is 5 arranged in closed position the intervening sections between the slots of the sleeve will serve to form a closure for the slots 6 of the casing. At one side of the sleeve I provide a downwardly depending arm 26 formed of 10 spring-like material with its lower end free to move inwardly with respect to the sleeve. At the lower end of the arm is formed a lug 27 having a substantially beveled edge at one side thereof whereby upon contact thereof 15 with an edge of one of the slots 6 the lug and the lower end of the arm will be forced inwardly whereby to engage the ball and move the same away from its seat 9. With the device in normal operating position as shown in 20 Figure 2 of the drawing, the pump rod may be freely operated to pump the oil from the well without permitting any return of the oil to the well when the ball 10 and the sleeve 24 are in closed position with respect to the 25 casing 5. Whenever it is desired to withdraw the pump rod from the well the oil collected in the upper part of the casing above my valve cage mechanism will be permitted to return to the well by slightly rotating the 30 upper end of the pump rod so as to register the slots 25 in the sleeve 24 with the slots 6 of the casing. Such rotary movement further operates to move the lug 27 against the edge of one of the slots 6 thereby forcing the 35 same inwardly against the ball 10 so as to unseat the same. It is further obvious that the parts may be returned to normally closed position by a further rotation of the upper end of the pump rod.

40 It is obvious that the invention is susceptible to various changes and modifications without departing from the spirit thereof or the scope of the appended claims and I accordingly claim all such forms of the device 45 to which I am entitled.

I claim:

1. A valve cage comprising a casing having a plurality of slots formed therein, a valve operatively arranged in the lower end 50 thereof, a stem extending from the upper end of said casing, means yieldably supporting the same therein, a sleeve rotatably arranged within the casing and releasably engageable with said stem and having slots adapted to 55 be arranged in alinement with the slots in the casing and means carried by the sleeve operatively engaging the valve whereby to open the same upon the alining of said slots and permitting the closing of said valve upon the 60 movement of said slots out of alinement.

2. A valve cage comprising a casing having a plurality of slots arranged therein, a ball valve arranged in the lower end of said

casing, a stem slidably arranged in the upper end of the casing and yieldably carried 65 therein, a collar fixedly carried on the lower end of said stem, a collar freely mounted on the stem, means carried by said collars releasably engaging the same, a sleeve formed on one of said collars arranged within the 70 casing and having a plurality of slots adapted to be moved into alinement with the slots in the casing, an arm carried by said last named collar having its lower end movable into and out of engagement with the ball of said 75 valve and a lug formed on said arm engageable with the casing co-acting with said valve whereby to open or close the same upon the movement of the slots in the sleeve and the casing into or out of alined position. 80

3. A valve cage adapted to be interposed in a pump rod and having a plurality of slots formed therein, a ball valve operatively arranged in the lower end of said cage, a stem arranged slidably in the upper end of the cage and yieldably supported therein, a collar fixedly mounted on the lower end of the stem within the cage, a collar freely carried on the end of the stem within the cage, means releasably connecting the collars for simultaneous rotation, a sleeve formed on said freely mounted collar arranged within the cage and having a plurality of slots adapted to be alined with the slots of the cage, an arm formed on said collar and a lug on said arm co-acting with the slots of the cage whereby to move the valve into open position upon the alining of said slots. 90

4. A valve cage for pump rods and the like comprising a tubular casing having a plurality of slots formed therein, a ball valve arranged in the lower end of said casing, a stem 95 slidably arranged in the upper end of the casing, a spring arranged on the stem engaging the casing whereby to normally maintain the same in outwardly extended position, a collar fixedly secured to the lower end of the stem within the casing, a collar freely mounted on said stem beneath said first named collar, ratchet teeth formed on the opposing faces of said collars, a spring arranged on the stem within the casing yieldably forcing the upper collar into engagement with the lower collar whereby to cause the simultaneous rotation thereof, a sleeve formed on said lower collar extending downwardly within the casing and having slots formed therein adapted to be moved into and out of alinement with the slots in the casing, an arm flexibly attached to the lower collar and a lug formed at the lower end thereof coacting with the slots in the cage whereby to move the valve into open position upon the alining of said slots. 100

In testimony whereof I affix my signature.

WILLIE NOEL MAGEE.
